SECURING CLIP FOR PREFORMED BOW TIE

Carysfort F. Lloyd-Young, Seattle, Wash.

Application August 29, 1958, Serial No. 758,141

5 Claims. (Cl. 24—81)

This invention relates to bow tie attaching clips and has reference more particularly to improvements in those forms of clips used for the securing of pre-formed bow ties to the wings of the collars of the shirts with which the ties are to be worn.

It is the principal object of this invention to provide a novel and also much simplified form of bow tie securing clip, that will more positively secured the tie in place than is accomplished by clips now generally used and that will not slip or pull loose from the collar wings incident to the wearer coughing, sneezing, turning the head or doing anything else that places the clip under more than ordinary strain.

It is also an object of the present invention to provide a clip that has substantial flexibility; that is easy to apply to the shirt collar; that will not cause the wing portions of the collar to which it is applied to be unduly worn, soiled or creased by reason of its use therewith.

More specifically stated, it is the primary object of the present invention to provide a bow tie securing clip whereby the above mentioned objects and advantages are attained; that is characterized by the use therein of clamping rollers that are mounted for swinging adjustment into and from collar clamping coaction relative to the opposite end portions of the frame plates to which the tie is secured.

In accomplishing the above mentioned and other objects of the invention, I have provided the improved details of construction, the preferred forms of which are illustrated in the accompanying drawings, wherein:

Fig. 1 is a front view of a bow tie, showing it as equipped with a securing clip embodying the improvements of the present invention therein, and showing the tie as secured by the clip to a shirt collar.

Fig. 2 is a front view of the clip and tie; the tie being shown only in dash lines and the clip showing one of the clamping rollers in released position and the other in clamping position.

Fig. 3 is a horizontal section, taken on line 3—3 in Fig. 2.

Fig. 4 is a vertical section taken on line 4—4 in Fig. 1.

Fig. 5 is a perspective view, showing parts of the clip frame in disconnected relationship for explanatory purposes.

Referring more in detail to the drawings:

In Fig. 1, a typical bow tie is designated by reference numeral 10 and the two wings of the collar portion of a shirt to which the tie is secured by the present clip are designated respectively by numerals 11 and 11x.

The present clip comprises a frame structure which has a central and horizontally disposed plate 12 that is enclosed lengthwise within the knot portion 13 of the pre-formed bow tie 10 as shown in Fig. 3, to the opposite end portions of which central plate, opposite end plates 14—14 are pivotally secured to serve as lateral extensions of the plate 12. These wing plates are enclosed within the opposite wing portions 13'—13' of the bow tie

2

and are secured thereto at their outer ends, as at 15—15 in Fig. 1.

Ordinarily the frame structure, as thus provided by the joined parts 12, 14 and 14, is approximately three and one-half inches long.

To best adapt the central plate to the present use, it is somewhat transversely curved, as best shown in Fig. 3. The wing plates 14—14 are each about twice the length of the central plate 12 and are quite narrow. 10 Also, they are inwardly concaved or troughed, as best shown in Fig. 4, and at their outer ends, the wing plates are formed with transversely directed flanges or tabs 16 which are rounded at their ends and are perforated to receive threads by which the tie can be sewed thereto. 15 The relationship of the frame forming parts 12 and 14—14 to each other and to the tie is as best shown in Fig. 2.

It is further to be understood, especially by reference to Figs. 3 and 5, that the wing plates 14—14 are equipped at their inner ends, at top and lower edges, with vertically aligned projecting pivots 18 which are contained in holes 19 of paired ears 20—20 that are outwardly turned from the top and lower edges of the plate 12 at its opposite ends. The manner of mounting of these 25 wing plates is such that their forward swinging movement relative to plate 12 is limited to the positions in which they are shown in Fig. 3, but their inward swinging movement is to a substantial angle, as an aid in attaching the clip to the collar wings 11 and 11x.

30 Associated with each of the wing plates 14—14 is a clamping roller 24. Each roller is mounted for easy turning on a supporting shaft 25 that is secured at its inner end by a pivot 26 to the back side of the corresponding plate 14 closely adjacent its inner end, as observed in Figs. 3 and 5. The rollers ordinarily would be approximately one inch long and one-fourth inch in diameter, and formed with encircling serrations 27, pointed inwardly as observed in Fig. 5, as an aid in securing the collar wings against pulling free when clamped 35 between the plates 14—14 and rollers. The mounting of the clamping rollers is such that they can be swung about the pivots 26 from positions extended along and close to the back sides of the wing plates, as shown in Fig. 3, to the downwardly directed angular positions 40 shown in Fig. 2.

45 Assuming that the bow tie 10 is equipped with a securing clip of the kind described, the application of the tie to a shirt collar is as follows: The clamping rollers 24—24 are first swung to their downwardly directed and released positions, and the tie placed in position across the 50 collar wings 11—11x as shown in Fig. 1. Then the rollers are swung upwardly and caused to pass beneath the collar wings 11—11x into parallel relationship with the plates 14—14. When in this position, each roller coacts with the corresponding plate 14 to firmly clamp the collar wing between them, as in Fig. 4, thus to secure the tie in position.

55 It is to be observed by reference to Fig. 4 that the roller 24 seats within the concaved under face of the corresponding plate 14 and thus its clamping position relative to the plate is automatically retained. Also, it can be understood, by reference to Fig. 3, that the encircling serrations 27 of the rollers will grip and hold the collar against being pulled free from between plate 60 and roller.

65 It is anticipated that in some instances the frame may comprise a single plate, in lieu of the pivotally joined plates 12, 14—14 and that the single plate could be curved or shaped to embody the features therein that are 70 found in the pivoted plates as herein employed. Also, it is possible to employ rubber rollers with or without serrations 27.

What I claim as new is:

1. A securing clip for pre-formed bow ties; said clip comprising a center plate, adapted for disposition within the knot forming portion of the tie, wing plates extending from opposite ends of said center plate and adapted to be attached to the opposite wings of the tie, and a clamping roller associated with each wing plate; each rotatably mounted on an axial shaft that is pivoted at one end to the inner end of the corresponding wing plate at the inside thereof; said rollers being adapted to be swung by their mounting shafts between a position extending along the inside of the corresponding wing plate for clamping one wing of a shirt collar between them, and a collar releasing position at an angle to the mounting plate to release the clamped collar wing.

2. The device of claim 1 wherein the said wing plates are hinged at their inner ends to the opposite ends of said center plate for swinging adjustment from positions

substantially aligned with the center plate, to positions at which they are rearwardly inclined.

5. The device of claim 1 wherein said rollers are circumferentially serrated to provide a collar gripping surface whereby pulling of the collar wings therefrom, when clamped will be prevented.

10. 4. The tie securing clip of claim 3 wherein said wing plates are longitudinally troughed to seat the rollers therein when adjusted to clamping position.

15. 5. The tie securing clip of claim 4 wherein said center plate has hinge ears turned outwardly therefrom at its opposite ends at its upper and lower edges and said wing plates have hinge pivots at their inner ends, at upper and lower edges that are pivoted in said hinge ears at corresponding ends of said center plate.
